4 Claims. (Cl. 101—91)

This invention relates to postage meters.

It is one object of this invention to provide improved postage meters, and more particularly to provide postage meters that can be operated in an easier or more convenient way than prior art postage meters.

Another object of this invention is to provide postage meters that lend themselves to be operated with one single hand.

Another object of this invention is to provide improved operating means for postage meters of the kind disclosed in United States Patent 2,187,456 to Erich Komusin, January 16, 1940, Printing Apparatus; in United States Patent 3,002,686 to Friedrich Heil and Horst Springer, October 3, 1961, Postage Meters, and in United States Patent 3,078,791 to Friedrich Heil, Selector for Postage Meters, February 26, 1963.

This invention is more particularly concerned with postage meters which are adapted to make an imprint on the surface of a letter, or a strip of paper, as the entire meter is being moved over the surface to be imprinted.

It is a further object of this invention to provide postage meters of the aforementioned character having selector means adapted to be operated by the same hand of an operator which is being used by him to move the meter over the surface to be imprinted.

Postage meters comprise selector means and type means which must selectively be brought into, and out of, engagement. During the adjusting operation of the meters, i.e. preparatory to the printing operation thereof, the selector means are brought into engagement, or operatively coupled, with the type means. The aforementioned selector means must be disengaged or uncoupled from the aforementioned type means when it is intended to operate the latter to make an imprint on a given surface to be imprinted.

It is a further object of this invention to provide postage meters adapted to be moved over the surface to be imprinted and having selector means, type means and coupling and uncoupling means for selectively coupling and uncoupling said selector means and said type means, wherein all said means are adapted to be operated by the same hand of the operator which is used by him to move the meter over the surface to be imprinted.

Other objects and advantages of the invention will, in part, be obvious and in part appear hereinafter.

For a more complete understanding of the invention reference may be had to the following detailed description of a preferred embodiment thereof taken in connection with the accompanying drawings in which:

FIG. 1 is in part an isometric side view and in part an isometric section showing the coupling mechanism between the selector means and the type means of a postage meter embodying the present invention, FIG. 1 further showing certain parts associated with the above coupling mechanism, the type means of the meter being omitted in FIG. 1;

FIG. 1a shows the same structure as FIG. 1 in a different operating position;

FIG. 2 is a side elevation of the meter structure shown in FIG. 1 as seen from the rear of FIG. 1 and shows some of the constituent parts of the meter in the rest position thereof and the hand of an operator ready to operate the meter; and

2

FIG. 3 is a side elevation of the meter structure shown in FIG. 1 as seen from the rear of FIG. 1 and shows some of the constituent parts of the meter in the operating position thereof and the hand of an operator operating the meter.

Referring now to the drawings, reference character 2 has been applied to indicate a side panel of the housing of the meter which panel is used as a mounting plate for supporting shaft 1. The latter has one end in the form of a screw head, as clearly shown in FIG. 1. Shaft 1 pivotally supports a coupling lever 3 which, in turn, supports a solid shaft 4. Mounted on solid shaft 4 are two hollow shafts 5 and 6 as can be seen in FIG. 2. Number disc 7 and gear 8 are integral with solid shaft 4. Number disc 9 and gear 10 are integral with hollow shaft 5, and number disc 11 and gear 12 are integral with hollow shaft 6. Each number disc is provided with a selecting lever or adjusting lever 13.

Reference numerals 14, 15 and 16 have been applied to indicate three gears adapted to operate the printing means of the meter which have not been illustrated in the drawings. Gears 14, 15 and 16 are mounted on solid shaft 17 and hollow shafts 18 and 19, respectively. Gears 8, 10 and 12 are adapted to be brought into and out of, meshing engagement with gears 14, 15 and 16. If the movement of number discs 7, 9 and 11 is to be transmitted to gears 14, 15 and 16 by the intermediary of gears 8, 10, and 12, coupling lever 3 must be pivoted about its shaft 1 to its operative position, i.e. in counterclockwise direction as seen in FIG. 1. Then gears 8, 10 and 12 are brought into meshing engagement with gears 14, 15, and 16. When gears 8, 10 and 12 are out of meshing engagement with gears 14, 15 and 16, each of the former is engaged by one of the three pawls 40. The operation of gear engaging pawls has no bearing on the present invention. Their operation is more fully described in the aforementioned U.S. Patent 3,078,791 to Friedrich Heil.

Coupling lever 3 supports a U-shaped bracket 38 which, in turn, supports by means of its flanges a shaft 39. Latching lever 20 is pivotally mounted on shaft 39. Bracket 38 is provided with a tab 21 having an aperture into which one end of a helical spring 22 is inserted. The opposite end of spring 22 is fastened to a pin 23 mounted on mounting plate 2 and projecting at right angles therefrom. Spring 22 biases coupling lever 3 in clockwise direction, as seen in FIG. 1, thus tending to maintain coupling lever 3 in its position of rest or second limit position, in which position coupling lever 3 is shown in FIG. 1. Tab 24 is integral with latching lever 20 and is adapted to be engaged by an abutment pin 25 supported by, and projecting at right angles from, plate 2. In the position of the parts of the meter shown in FIG. 1 tab 24 and pin 25 are in abutting engagement.

It will be apparent from FIG. 1 that plate 2 and coupling lever 3 are arranged in parallel planes and that latching lever 20 is movable at right angles to the aforementioned parallel planes.

Latching lever 20 supports a pin 26 projecting rearwardly as seen in FIG. 1. Plate 2 is provided with a substantially U-shaped cut-out adapted to be engaged by pin 26 of latching lever 20. Latching lever 20 is under the bias of a rat-trap-spring 28 mounted on shaft 39 and biasing latching lever 20 in such a fashion that pin 26 tends to enter into, or engage, U-shaped cutout 27. Such engagement can, however, only occur when coupling lever 3 has been pivoted about shaft 1 from its rest position or second limit position shown in FIG. 1 to its operating position, or first limit position, i.e. when coupling lever 3 has been pivoted in counterclockwise direction against the bias of spring 22 from its position shown in FIG. 1. Latching lever 20 is provided with an operating member 29 intended to be engaged by the forefinger

of the operator of the meter in order to shift coupling lever 3 from its position of rest to its operating position.

The upper surface 30 of the housing of the postage meter is provided with another operating member 31 intended to be engaged by the right thumb 32 of the operator of the meter. Operating member 31 has two functions. It forms abutment for positioning the right thumb 32 of the operator and is in the shape of a convex tab substantially conforming to the shape of the surface of the operator's right thumb. Member 31 is referred to as an operating member because of its second function which is to make it possible for the operator of the postage meter to grasp the meter to move the entire meter bodily over the mail to be postmarked. When the right thumb 32 of the operator engages operating member 31, the tip of thumb 32 is situated right over the levers 13 for operating the number discs 7, 9, and 11. In that particular position of the hand of the operator his forefinger 33 can readily reach the operating member 29 of the latching lever 20. Operating member 29 is provided with an outer pressure receiving surface 34 adapted to be abuttingly engaged by the tip of the right forefinger of the operator of the postage meter. Applying pressure against outer pressure-receiving surface 34 of operating member 29 causes a pivotal movement of coupling lever 3 from its position shown in FIG. 1 to its operating position. When coupling lever 3 has been pulled to the later position pin 26 of latching lever 20 snaps into cut-out 27 and latches coupling lever 3 firmly in position. Now the operator of the meter may at will readily adjust the three number discs 7, 9, and 11. This is effected with the tip of his thumb 32 by manipulating levers 13 and without changing the general position of his right hand, or removing his right hand from the postage meter.

The outer end of shaft 4 supports a disc of sheet metal having a lateral arm 36 projecting over number discs 7, 9, 11. Lateral arm 36 is provided with a rectangular cut-out or window 35 exposing to view the number selected by manipulating selector or adjusting levers 13.

Operating member 29 is provided with a front abutment or pressure-receiving surface to which reference numeral 37 has been applied. Applying a short pressure impulse upon abutment or pressure-receiving surface 37 causes pin 26 to be moved out of cut-out 27, thus allowing lever 3 to be retracted under the bias of spring 22 to its position of rest or second limit position shown in FIG. 1.

Now the meter is ready to be moved by the hand of the operator over or across the surface to be imprinted. While this is effected the hand of the operator remains still in the initial position thereof, in which position coupling of the type adjusting gear 14, 15, 16 of the meter with the selector discs 7, 9, 11 thereof, adjustment of the latter and uncoupling of the type adjusting gears 14, 15, 16 of the meter from the selector discs 7, 9, 11 thereof has been carried out.

It will be apparent from the foregoing that postage meters embodying this invention comprise a housing having a top surface 30 and having a lateral surface or plate surface 2 forming an edge at this intersection of the aforementioned two surfaces. The levers 13 for controlling the number discs 7, 9 and 11 and the dual function operating member 29 for manually coupling and uncoupling gears 8, 10, 12 and gears 14, 15, 16 and for releasing the latching mechanism 26, 27 are arranged close to the forementioned edge and so is the thumb engaging abutment part 31. Thus parts 13, 29, and 31 can readily be reached by various fingers of the hand of the operator without the need of changing the position of the entire hand relative to the casing or housing of the postage meter.

It will also be observed that the distance between adjusting levers 13 and the position of operating member 29 when coupling lever 3 is in its second limit position (FIGS. 1 and 3) is less than the distance of the span between the tip of a forefinger and the tip of the thumb of a postage meter operator.

Coupling lever 3 and latching lever 20 are adapted to pivot in different directions relative to plate 2 and spring 22 and 28 are adapted to bias levers 3 and 20 in different directions. Pressure exerted against the pressure-receiving surface 34 of operating member 29 causes joint movement of coupling lever 3 and of latching lever 20 from the second limit position shown in FIGS. 1 and 3 to the first limit position shown in FIG. 2. This pivotal movement is effected against the bias of spring 22. The second pressure-receiving surface 37 of operating member 29 is arranged at an angle to pressure-receiving surface 34. Pressure exerted against the pressure-receiving surface 34 of operating member 29 causes disengagement of parts 26 and 27 against the bias of rat-trap-spring 28.

FIG. 1a shows the coupling lever 3 in its operative position, or first limit position, when moved counterclockwise from the position shown in FIG. 1.

It will be understood that I have illustrated and described herein a preferred embodiment of my invention, and that various alterations may be made in the details thereof without departing from the spirit and scope of my invention as defined in the appended claims.

I claim as my invention:

1. A postage meter comprising in combination:
- (a) selector means;
- (b) type adjusting means;
- (c) a pivotable coupling lever supporting said selector means, said coupling lever having a first limit position for causing operative engagement between said selector means and said type adjusting means and said coupling lever having a second limit position for causing operative disengagement of said selector means from said type adjusting means;
- (d) a first pivot means supporting said coupling lever;
- (e) a latching lever;
- (f) a second pivot means arranged angularly with respect to said first pivot means supported by said coupling lever and supporting said latching lever;
- (g) fixed latching means adapted to be engaged by said latching lever to maintain said coupling lever in said first limit position thereof;
- (h) a first spring exerting a bias upon said coupling lever in a direction from said first limit position thereof to said second limit position thereof;
- (i) a second spring tending to cause resilient engagement between said latching lever and said fixed latching means, said second spring exerting a bias upon said latching lever in a direction angularly related to said first mentioned direction; and
- (j) an operating member integral with said latching lever for manipulating said coupling lever against the bias of said first spring and for manipulating said latching lever against the bias of said second spring.

2. A postage meter comprising in combination:

- (a) a housing having a top surface and lateral surfaces;
- (b) a first operating member on said top surface forming an abutment adapted to be engaged by a finger of a meter operator to move said housing over matter to be imprinted;
- (c) a plurality of pivotable number discs on one of said lateral surfaces arranged immediately adjacent said first operating means;
- (d) a plurality of number disc gears each integral with one of said plurality of number discs;
- (e) a plurality of type adjusting gears;
- (f) a movable coupling lever supporting said plurality of number discs and said plurality of disc gears, said coupling lever being adapted to be moved to a first limit position for causing operative engagement between said plurality of number disc gears and said plurality of type adjusting gears and to be moved to a second limit position for causing operative disengagement of said plurality of number disc gears from said plurality of type adjusting gears;

- (g) a latching means supported by and movable relative to said coupling lever for latching said coupling lever in said first limit position thereof;
  - (h) a first spring exerting a bias upon said coupling lever in a direction from said first limit position thereof toward said second limit position thereof;
  - (i) a second spring for rendering said latching means operative biasing said latching means in a direction angularly related to said first mentioned direction; and
  - (j) a second operating member integral with said latching means for moving said latching means jointly with said coupling lever against the bias of said first spring from said second limit position thereof to said first limit position thereof and for effecting 15 relative movement between said latching means and said coupling lever against the bias of said second spring means, said second operating member being arranged sufficiently close to said first operating member to allow said first operating member and said second operating member to be engaged by different fingers of the same hand of an operator of the postage meter.
3. A postage meter comprising in combination:
- (a) selector means;
  - (b) first shaft means supporting said selector means;
  - (c) type adjusting means;
  - (d) second shaft means arranged parallel to said first shaft means;
  - (e) a coupling lever defining a general plane pivotally supported by said second shaft means and supporting said first shaft means, said coupling lever having a first limit position for causing operative engagement between said selector means and said type adjusting means and said coupling lever having 30 a second limit position for causing operative disengagement of said selector means from said type adjusting means;
  - (f) a supporting plate arranged parallel to said gen-

- eral plane and supporting said second shaft means;
  - (g) pivot means on said coupling lever defining a pivoting axis extending substantially parallel to said general plane;
  - (h) a latching lever supported by said pivot means pivotable within a plane substantially at right angles to said general plane;
  - (i) a fixed latching means formed by a portion of said plate adapted to be cooperatively engaged by said latching lever;
  - (j) a first spring interposed between said coupling lever and said plate biasing said coupling lever from said first limit position thereof toward said second limit position thereof;
  - (k) a second spring interposed between said coupling lever and said latching lever tending to bias said latching lever into engagement with said fixed latching means; and
  - (l) an operating member integral with said latching lever for manipulating said latching lever and said coupling lever through the intermediary of said latching lever.
4. A postage meter as specified in claim 3 wherein said operating member is provided with a first pressure-receiving surface for pivoting said latching lever and said coupling lever jointly against the bias of said first spring, and wherein said operating member is provided with a second pressure-receiving surface arranged at an angle to said first pressure receiving surface for pivoting said latching lever relative to said coupling lever against the bias of said second spring.
